GRANT HAMMOND, OF NEW HAVEN, CONNECTICUT, ASSIGNOR OF ONE-THIRD TO ALVA C. WASHBURN, OF PITTSFIELD, MASSACHUSETTS, AND ONE-THIRD TO FREDERICK G. CRANE, OF DALTON, MASSACHUSETTS.

MAGAZINE FOR FIREARMS.

1,348,172.

Specification of Letters Patent.

Patented Aug. 3, 1920.

Application filed February 28, 1918. Serial No. 219,591.

To all whom it may concern:

Be it known that I, GRANT HAMMOND, a citizen of the United States residing at New Haven, in the county of New Haven and 5 State of Connecticut, have invented a new and Improved Magazine for Firearms, of which the following is a specification.

My invention relates more especially to the class of devices used to contain a number 10 of cartridges in a magazine chamber in a firearm of the "automatic type," and an object of my invention, among others, is to provide a magazine of such inexpensive character that it may be discarded after a single 15 use, and which magazine shall at the same time be sufficiently strong to withstand all of the strains in use.

One form of device embodying my invention and in the construction and use of 20 which the objects herein set out, as well as others, may be attained, is illustrated in the accompanying drawings, in which—

Figure 1 is a view in side elevation of a magazine embodying my invention.

Fig. 2 is a view in edge elevation, with the lower part broken away to show construction.

Fig. 3 is a view in cross section on plane denoted by dotted line 3—3 of Fig. 1.

Fig. 4 is a view of a blank from which my improved magazine is made.

My improved magazine is formed from a single piece of metal that is first cut or stamped to form a blank comprising side 35 sections 5 and 6 united by an edge section 7 having rib sections 8 at opposite edges. Bottom tabs 9 are formed at one end of each of the sections 5 and 6 and the section 6 has a notch 10 in one end that, in the use of the 40 magazine, receives a lug on a releasing bar and permits said lug to be engaged by the follower in the magazine.

The blank is bent to shape on the dotted lines 11 to form the side parts and back edge, 45 and the edges 8 are bent on the dotted lines 12 to form the front edge of the magazine.

In the use of magazines in firearms, and especially of the "automatic type" a peening action is produced upon the front edge 50 of the magazine by reason of the recoil under the forces of the gases of explosion

driving the magazine backwardly against the noses of the cartridges in said magazine, the cartridges being of considerable weight and, therefore, unable to quickly overcome 55 inertia. In order to prevent injury to the magazine from such peening action I provide a rib extending lengthwise along the center of the front edge of the magazine, this being of special advantage in a magazine 60 constructed of thin sheet metal, as shown herein, as it enables much thinner metal to be used than could otherwise be employed did this rib not exist.

In constructing this rib, the edges 8 are 65 bent backwardly and interlocked in the manner of the well known "stove-pipe joint" and a rib 13 is thus produced which will effectively resist the peening action hereinabove mentioned.

The top edges of the side sections of the blank are formed at an angle to the lines 11 as denoted by the numerals 14, these angularly disposed edges being separated by a curved recess 15 and terminating in notches 70 16. These edges serve as lip sections 17, and when the blank is bent into final shape to form a magazine 18, these lip sections 17 are readily shaped to provide lips 19 on the magazine with an opening 20 between them 75 80 constituted by the recess 15. In this final shaping of the magazine the tab sections 9 are bent inwardly and rest one against the other to form the bottom 21 as shown in Fig. 2 of the drawings.

In accordance with the provisions of the patent statutes, I have described the principles of operation of my invention, together with the device which I now consider to represent the best embodiment thereof; but I 90 desire to have it understood that the device shown is only illustrative, and that the invention may be carried out by other means.

I claim—

A magazine blank comprising two side 95 sections each having a portion of one end located at an angle to a longitudinal line through said sections, and each angularly disposed end terminating in notches, and said notches terminating in curved portions 100 extending to opposite edges of the blank.

GRANT HAMMOND.
